BLOCKOUT SHIFTING MEANS FOR ROTARY DUPLICATING MACHINES

Carl A. Levin, Park Ridge, Ill., assignor to Ditto, Incorporated, Chicago, Ill., a corporation of West Virginia

Application May 26, 1950, Serial No. 164,405

9 Claims. (Cl. 101—132.5)

This invention relates to apparatus for line printing, and in particular to improved means for shifting a block-out and a feed tray in unison.

In one method of line printing, a stack of narrow or strip-like copy sheets are shifted laterally in a step by step manner on a feed table of a duplicating machine. Thus, different portions of a master, mounted on the drum, will be duplicated on successive copy sheets. This method can be used in payroll systems to pick up the names of and amounts payable to various employees, this information appearing in list form on the master sheet. In other words, the master sheet is a payroll list. By using a semi-automatic feed tray shifting device, such as that described in my copending application Serial No. 138,841, filed January 16, 1950, now U. S. Patent No. 2,660,431, a very efficient method of preparing pay checks is provided. However, the spacing between the blocks of printed matter on the master sheet must be equal to the width of the copy sheet, or in the alternative, a blockout must be used which requires manual shifting and adjustment.

According to the present invention, I have provided a block-out which is automatically shifted in unison with the feed tray or copy sheet guide. Thus, the blocks of printed matter may be closely spaced to each other which permits more information to be carried on the master sheet.

Another object of my invention is to provide means for connecting the feed tray and the block-out which is readily removable and adjustable.

A still further object of my invention is to provide a magnetic block-out which is self-aligning and which is readily shiftable, in comparison with the block-outs of the prior art.

A still further object of my invention is to provide an improved block-out which is provided with an upstanding portion for engagement with a laterally shiftable connecting device, but which upstanding portion does not interfere with the operation of the duplicating machine.

Other objects, features and advantages will become apparent as the description proceeds.

With reference now to the drawings in which like reference numerals designate like parts:

Fig. 1 is a plan view of a duplicating machine embodying a preferred form of my invention;

Fig. 2 is a vertical section taken along line 2—2 of Fig. 1;

Fig. 3 is a partial section through the drum taken along line 3—3 of Fig. 2;

Fig. 4 is a perspective view showing the cooperation between the connecting arm and the block-out;

Fig. 5 is a plan view of the parts shown in Fig. 4;

Fig. 6 is a section taken along line 6—6 of Fig. 3 showing the adjustable and removable mounting of the connecting arm;

Fig. 7 is an enlarged section taken along lines 7—7 of Figs. 3 and 5 showing the construction of the magnetic marginal portion;

Fig. 8 is a section taken along line 8—8 of Fig. 5; and

Fig. 9 is a view of one of the copy sheets after duplication thereon.

With reference now to Figs. 1 and 2, the duplicating machine comprises a suitable frame 10 in which is rotatably mounted a drum 11. The duplicating machine

2

also includes a feed table 12, a pressure roll 13, feeding and moistening rolls 14, and a moistener 15. All of the foregoing parts are standard in duplicating machines of this wet process type.

5 The drum includes the usual grippers 16 by means of which a master sheet M may be mounted on the drum. The drum is of the so-called magnetic block-out type, and as such is provided with a slot 17 disposed just forwardly of the grippers. Magnets 18 are suitably mounted 10 within the interior of the drum, and pole pieces 19 extend outwardly from the drum and through suitable apertures in the bottom wall 20 of the slot.

The block-out is indicated generally by the reference numeral 21 and is provided with a magnetic marginal portion 22 which is adapted to fit into the slot 17 and engage the bottom wall 20. The block-out is held in position by the magnetic attraction afforded by the magnets and the pole pieces, and this arrangement permits easy removal and insertion of a block-out.

15 The block-out includes a blocking portion 23 which is made of flexible stainless steel sheet of a thickness of approximately .002 inch. The blocking portion may be provided with a slot 24 which is of a width which corresponds to the width of the blocks 29 of typed material which appears on the master sheet M. Thus, the block-out can be shifted laterally to expose one block after another so that each block of typed material can be duplicated onto successive copy sheets.

The copy sheets are stacked in a feed tray 25. Although the feed tray is shown as having flange portions 36 to engage both sides of the stack, it may constitute just a single side guide in certain situations. The feed tray is slidably or shiftably mounted in slots 26 in the feed table 12, and the feed tray may be shifted, by depressing the operating lever 27, in a step by step manner by a suitable mechanism which is shown and described in the aforesaid copending application. Sheet advancing means in the form of intermittently operating rollers 28, the construction and operation of which are described 35 in said copending application, are provided for advancing the top copy sheet of the stack disposed in the feed tray into operative engagement with the drum.

40 Means are provided to connect the feed tray with the block-out so that as the feed tray is shifted through a distance corresponding to the spacing between the blocks 29, the block-out will be shifted accordingly so as to expose the next succeeding block 29 on the master sheet. This means comprises a connecting member 30 which is removably mounted on the feed tray at its rear end, and which engages at its front end a yoke portion 45 of the block-out.

The connecting member preferably comprises a strip of steel which is provided with a reinforcing flange 37 and which at its lower front end is further reinforced by a plate 38 which is welded or otherwise secured to the side surface of the connecting member 30. The connecting member is rigidly mounted on a block 32 by means of a washer 33 and a screw 34. A clip 35, suitably secured to the top surface of the block, extends 50 downwardly over one side and is adapted to engage the right flange 36 of the feed tray as shown in Fig. 6. The clip is preferably of substantial length so as to provide a good frictional grip between the block and the flange which will serve to prevent wobbling of the connecting member 30.

55 The yoke portion 31 is in the form of a sheet of spring stainless steel of substantially .005 inch. The sheet is bent to provide a base portion 40 and two legs 41. The base portion may be welded or otherwise secured to the underside of the flexible sheet 23 so that the legs 41 will extend away from the drum. The legs are so shaped as to form an outwardly converging slot 42 which is adapted to receive the forward end of the connecting member 30. The slot is of converging shape so as to compensate for any possible overthrow incident to the operation of the feed tray shifting mechanism. As the drum rotates in the counterclockwise direction out of its home position as shown in Fig. 2, the block-out will cam itself into the proper position due to the converging edges of the slot. The lower edge of the connecting

member is of arcuate shape so that it will lie closely against the drum surface, as shown in Fig. 2.

The magnetic marginal portion 22, as shown in Fig. 7, includes clip 44 of magnetic material, such as iron, which is folded so as to engage the edge of the flexible stainless steel sheet 23. The stainless steel is preferably a non-magnetic stainless steel and it will be observed that it extends around the underside of the iron clip so as to space the iron clip 44 from the pole piece 19. Thus, an air gap is provided which reduces the magnetic force to an extent whereby the block-out may be readily shifted in the slot 17. It has been found that where such an air gap is not provided, that the block-out cannot readily be shifted by means of the arrangement herein shown, or in the alternative, the block-out will tend to buckle or tear.

The block 32 is preferably of substantial mass so as to serve as a counterbalance in tending to maintain the connecting member 30 in its upright position. Thus, the torque or force which is applied to the clip in a direction parallel to the surface of the flange is somewhat reduced. This partially counterbalanced construction reduces the comparatively heavy friction grip which would otherwise be required to avoid sliding or rocking movement of the clip on the flange. Furthermore, the comparatively light frictional grip permits the connecting member as a whole to be readily removed when line printing is not desired.

I claim:

1. Shiftable block-out means for a duplicating machine having a drum, a pressure roll for cooperation therewith, means for stopping the drum in a home position, a feed table, and feed tray means shiftably mounted on said feed table for movement parallel to the axis of said drum and including a longitudinally oriented upstanding flange, said drum embodying means for receiving at its periphery an axially shiftable magnetic block-out, comprising the combination of a magnetic block-out, a block adapted to be disposed adjacent to said flange and removably secured thereto and supported thereby, an arm mounted on said block in a cantilevered manner and extending upwardly toward and engaging said block-out when said drum is in home position, said block being of substantial mass so as to counterbalance said arm to maintain the same in its upright position without the use of an intermediately disposed cross bar.

2. Shiftable block-out means as claimed in claim 1 in which said arm is in the form of a strip disposed in a vertical plane and is provided with a reinforcing flange extending into proximity to said block and a reinforcing plate secured to the surface of said arm at its lower end and extending upwardly beyond the lowermost extremity of said flange whereby said arm is reinforced against flexing in a lateral direction.

3. Shiftable block-out means as claimed in claim 1 in which said block-out is provided with a projecting portion which extends outwardly away from the surface of said drum and is engaged by the upper end of said arm, said projecting portion being resilient so that it may pass by said pressure roll as said drum rotates.

4. Shiftable block-out means as claimed in claim 3 in which said projecting portion is in the form of a yoke having outwardly converging legs, said legs defining a slot in which said upper end of said arm is received as said drum rotates into home position, whereby said

block-out may cam itself into a predetermined lateral relationship with said arm as said drum rotates away from home position.

5. Shiftable block-out means for use in a duplicating machine in which the drum is provided with an axially oriented slot in its periphery and with magnetic means for maintaining an axially shiftable magnetic block-out in said slot and for permitting transverse movement of said block-out in said slot comprising, in combination, said magnetic block-out and actuating means therefor to shift the same transversely, said magnetic block-out including a projecting portion which extends outwardly away from the surface of said drum when said magnetic block-out is mounted in said slot, and said actuating means comprising an arm, a block secured to one end of said arm, and a clip for engaging the upper edge of the flange of a transversely shiftable side guide, said block and said clip cooperating to hold said arm cantilevered in an upright operative position in which the opposite end of said arm will engage said projecting portion of said block-out whereby transverse movement of said side guide will be transmitted by said actuating means to said block-out to cause the same to shift transversely in said slot.

6. Shiftable block-out means as claimed in claim 5 in which said magnetic block-out includes an elongate member of magnetic material for insertion into said slot, and which includes non-magnetic spacing means disposed between said magnetic means and said elongate member for maintaining said elongate member out of direct contact with said magnetic means to facilitate the lateral movement thereof.

7. Shiftable block-out means as claimed in claim 6 in which said block-out includes a flexible block-out portion of non-magnetic material secured to said elongate member.

8. Shiftable block-out means as claimed in claim 7 in which said flexible block-out portion is wrapped around the edge of said elongate member to constitute said spacing means.

9. A connecting member for connecting the feed tray and the block-out of a duplicating machine comprising a block, a friction clip secured to said block and having a portion overhanging one side surface thereof, whereby said block can be frictionally secured to the upstanding flange of a feed tray, and an extending arm secured to said block and disposed in a plane which is parallel to said side surface, said block being of substantial mass so as to counterbalance said arm with respect to the center of rotation provided by the point of engagement of the forward edge of said clip and said upstanding flange.
